UNITED STATES PATENT OFFICE.

WILLIAM E. LANNING, OF LA PORTE, IOWA.

DESIGN FOR A STAPLE-PULLING IMPLEMENT.

SPECIFICATION forming part of Design No. 30,323, dated March 7, 1899.

Application filed January 25, 1899. Serial No. 703,387. Term of patent 14 years.

To all whom it may concern:

Be it known that I, WILLIAM E. LANNING, a citizen of the United States, residing at La Porte city, in the county of Black Hawk and State of Iowa, have invented and produced a new and original Design for a Staple-Pulling Implement; and I do hereby declare the following to be a full, clear, and exact description of the same, reference being had to the accompanying drawings, forming a part thereof.

This invention relates to a new and original design for staple-pulling implements, and it is embodied in the construction shown in the accompanying drawings.

15 In the drawings, Figure 1 is a side elevation of the device. Fig. 2 is an edge view.

The design, as illustrated in the drawings, consists in a central or stem portion A, cylindrical in cross-section, one end of which is 20 turned back to form a hook B. The opposite end of the stem or rod is bent to one side of the central portion, then bent or curved back to form a head C, crossing the line of the

stem, and then projects laterally to the other side of the central portion of the stem and 25 extends at an angle thereto. The head portion C and the end portion are flattened, and the end portion c is also drawn down to a point or penetrating edge.

The essential features of the design, as represented, consist in the central portion having the flattened head portion C, substantially as described, at one end and the hook portion at the opposite end.

Having thus described the invention, what 35 I claim as new, and desire to secure by Letters Patent, is—

The design for a staple-pulling implement, substantially as shown and described.

In testimony whereof I affix my signature 40 in the presence of two witnesses.

WILLIAM E. LANNING.
